GOLF CLUB CARRIER

Richard K. Samuelson, Indianapolis, Ind.

Application February 24, 1947, Serial No. 730,262

4 Claims. (Cl. 280—51)

1

The present invention relates to improvements in golf club carriers, particularly to that type of golf club carrier having a wheeled support by which the same may be trundled over the ground.

It has for one of its objects the provision of a carrier providing individual pockets for the respective clubs, whereby the clubs may be kept separated and more readily identified for the purpose of extraction for playing purposes.

It has for another of its objects the provision of a wheel mounting so arranged that the carrier may be trundled over the ground with a minimum of effort, a wheeled support being so constructed that it, in its entirety, may be removed from the club carrier to permit the carrier to be transported independently of the wheeled support and the support being further constructed so that it may be disassembled for shipping or packing purposes.

A further object of the invention is the provision of a handle by which the carrier may be trundled over the ground, the handle being so arranged that under certain conditions, as for instance on the side of a hill, the handle can be used to maintain the carrier in an inclined position and in such a position that the clubs will be readily accessible.

For the purpose of disclosing the invention, I have illustrated an embodiment thereof in the accompanying drawings, in which:

Fig. 1 is a side elevation of a golf club carrier embodying my invention;

Fig. 2 is a perspective view of the frame of the carrier;

Fig. 3 is a perspective view, looking downwardly and forwardly at the carrier;

Fig. 4 is a detail section on the line 4—4 of Fig. 1;

Fig. 5 is a detail of the mounting plate for the axles of the wheels;

Fig. 6 is a detail side elevation of the handle joint;

Fig. 7 is a detail section of the handle joint latch; and

Fig. 8 is a detail section on the line 8—8 of Fig. 1.

In the embodiment of the invention illustrated, I provide a lightweight frame 1, which comprises a flat oval top piece 2 and a corresponding oval bottom ring 3. The opposite ends of the oval top plate and bottom ring are connected together by longitudinally extending braces 4—4, which are comparatively wide and are curved to conform to the shape of the end pieces. These braces 4—4 are preferably riveted or otherwise

2

secured to the top and bottom pieces. The sides of the top and bottom pieces are connected together by vertically extending braces 5—5, which are connected to the sides of the top and bottom members at diametrically opposite points. Intermediate transversely extending braces 6 extend between the oppositely disposed braces 5 and these intermediate braces are connected to braces 7, thereby tying the intermediate portion of the frame together. Diverging braces 8 extend from the intermediate braces 6 to the end braces 4—4. As many sets of brace structures, as above described, may be provided as desired, although I have found that two sets give sufficient rigidity to the structure.

Covering this frame structure is a tubular oval-shaped sleeve 9, which extends to a point terminating at the bottom of the frame. This sleeve may be formed of canvas, leather, or any suitable material. The top edge of this sleeve is secured to the top member 2 in a manner to be more fully hereinafter described, and the bottom edge of the sleeve is riveted or otherwise secured to the oval or bottom ring 3. The pockets for the reception of the clubs are formed by a supplemental tubular sleeve considerably greater in diameter than the primary sleeve and folded or looped to form loops, as at 10, the material between the loops being stitched at the points 11 to the inner sleeve. The bottom edge of the outer sleeve terminates at a point short of the bottom of the framework, thereby leaving an open bottom tubular pocket extending from the top to the bottom of the frame. For closing the bottom of the pockets, I provide a bottom plate 12 having an upwardly turned flange 13 embracing the bottom ring 3 and riveted or otherwise secured thereto and the top edge of this upwardly turned flange 13 is provided with an outwardly turned flange 13', which extends beneath the open bottoms of the tubular pockets 10 and provides a shelf or base on which the bottoms of the clubs may rest.

In order to maintain the pockets 10 rigidly open at the top, I provide a looped metal brace 14, which is riveted to the top plate 2 and secured in position, after the inner sleeve has been placed in position. In this manner, the top edge of the inner sleeve is secured to the top plate 2. The loops forming the pockets 10 are brought over the outer edges of the metal loop 14 and preferably a reinforcing folded edge of leather or like material is secured over the top edge of the outer sleeve and the loop 14. This reinforcing binding may be extended downwardly at its inner edges

sufficiently far to permit stitching to secure the same in position. The outer sleeve is riveted or otherwise secured to the metal loop 14 intermediate of the folds.

By the above structure, I am enabled to provide an extremely lightweight pocketed golf club carrying structure readily transportable as a unit in itself. In addition to the pockets for the golf clubs, I provide a supplemental pocket 15 which may be formed of canvas or like material and secured through the outer and inner sleeves directly to the frame, preferably to one of the vertical braces 4. Likewise, a carrying handle 16 may be secured directly to one of the frame pieces 4 as well as a carrying strap 17. Near the lower end of the structure above described, and on the brace opposite the brace to which the handle 16 and strap 17 are secured, I mount a wheeled carrying bracket 18. The bracket is provided with a pair of ears 19 and 19', the ear 19 being provided with a vertical slot 20 and the ear 19' being provided with a transversely extending slot 21. Secured to one of the vertical frame braces 4 are a pair of threaded studs 22, which are vertically spaced on the frame, the proper distance to receive the vertical slot 20 and the transverse slot 21. The bracket, therefore, may be readily placed in position, by slipping the slot 20 transversely over the bottom stud and swinging the transverse slot on to the upper stud. These studs may be headed to prevent the displacement of the bracket or, as illustrated, wing nuts 23 are screw threaded upon the studs to securely clamp the bracket in position.

The bracket has secured thereto a transversely extending axle sleeve 24 and into the opposite ends of this axle sleeve 24 are inserted axles 25 removably carrying at their outer ends wheels, preferably of the rubber tired type, 26. The axles 25 are maintained in position, after having once been inserted in the sleeve 24 by suitable cotters or other pins 27, which are adapted to pass through the sleeve and through the axles.

A second pair of studs 28 are secured to the upper portion of the frame and on these studs is removably mounted a handle 29. This handle 29 is provided with an angularly disposed flat portion 30 having openings adapted to receive the ends of the studs 29 and being provided with wing nuts 31, by which the handle may be clamped in position. This handle is upwardly and rearwardly inclined from the club carrying structure and at its outer end, is provided with a down-turned hollow sleeve 32 having bifurcated ends 33, between which is pivoted on the pivot pin 34 a supporting leg 35. Normally, this leg is adapted to be maintained in its non-operative folded position, as indicated in dotted lines, being maintained in this position by a suitable clip 36 on the handle 29, as well as by a latch 37, which comprises the T head of a T-shaped member, the stem 38 of which projects into the top of a hollow leg 35. The head 37 operates in a slot 39 in the leg 35 and is biased in a latching position by a coiled spring 40. In the bifurcated legs 33, I provide a pair of notches 41 and 42 so positioned that when the head 37 snaps into the notch 41, the leg 35 will be maintained in an upright supporting position. When, however, the leg is folded under the handle 29 until the bar 37 engages, in the notches 42, the leg will be maintained in position parallel and on the underside of the handle 29, this latch supplementing the clip 36.

I claim as my invention:

1. A golf club container comprising an elongated tubular rigid frame including a plurality of longitudinally extending spaced apart side ribs, a tubular sleeve embracing said frame, a plurality of longitudinally disposed parallel tubular club handle containers secured to the outer face of said sleeve, and a pair of supporting wheels removably secured to the lower end of one of said ribs.
2. A golf club container comprising an elongated tubular rigid frame including a plurality of longitudinally disposed spaced apart side ribs, a tubular sleeve embracing said frame, a plurality of longitudinally disposed parallel tubular club handle containers secured to the outer face of said sleeve, a bracket removably secured to the lower end of one of said ribs, a transversely extending sleeve carried by said bracket, and a pair of axles, each having a wheel mounted thereon mounted in said sleeve.
3. A golf club container comprising an elongated tubular rigid frame including a plurality of longitudinally disposed spaced apart ribs, a sleeve surrounding said frame, and a plurality of longitudinally disposed parallel tubular club handle containers secured to the outer face of said sleeve, a pair of vertically aligned studs secured to the lower end of one of said ribs, a bracket removably secured to said studs, and a pair of wheels having their axles supported from said bracket.
4. A golf club container comprising an elongated tubular rigid frame including a plurality of longitudinally disposed spaced apart ribs, a sleeve surrounding said frame, a plurality of longitudinally disposed parallel tubular club handle containers secured on the outer face of said sleeve, a pair of vertically aligned studs secured to the bottom end of one of said ribs, a bracket removably secured to said studs and wheels having their axles mounted on said bracket, a second pair of vertically aligned studs secured to the upper end of said last mentioned rib and a handle removably secured to said second pair of studs.

RICHARD K. SAMUELSON.
